UNITED STATES PATENT OFFICE.

MICHAEL J. RILEY, OF EAST CLEVELAND, OHIO.

BOLT MACHINE.

Application filed September 7, 1920. Serial No. 408,550.

To all whom it may concern:

Be it known that I, MICHAEL J. RILEY, a citizen of the United States, residing at East Cleveland, in the county of Cuyahoga, 5 State of Ohio, have invented certain new and useful Improvements in Bolt Machines, of which the following is a specification.

While in some aspects of more general application the invention relates particularly 10 to a machine which will automatically size under the head of a headed blank or bolt or which will automatically shave or finish the top of such head or perform both operations.

In general the invention includes a hopper 15 into which the blanks or bolts may be thrown promiscuously. They may be assorted and arranged and passed from the hopper to a chute at the end of which they may be received by suitable mechanism for delivering 20 them into position to be grasped and held or rotated while a cutting device may operate on them.

In one aspect the invention includes a 25 spindle provided with a chuck or collet for grasping the work associated with means for rotating the spindle and operating the collet and cutters which may be moved to suitably attack the work. The cutters may have movement transverse to the axis of the 30 work or parallel thereto or in both directions. A support for the work may be provided near the point of attack by the cutting tools. The support itself may have suitable movement to adapt it to the work 35 and to allow of ingress and egress of the work.

One phase of the invention contemplates 40 picker fingers which bring the work into alignment with the collet so that it may be grasped. Associated with the picker fingers may be a positioning device tending to properly hold the work before the collet to 45 be grasped. The positioning device may be resiliently or yieldingly mounted. A device may be provided for kicking the work from the picker fingers in their retracted position and this device may move with the fingers.

The spindle may be mounted in a head adjustable toward and from the picker fingers 50 and the cutting tools and may be associated with mechanism for reciprocating it and for operating the collet carried by it so arranged that when the relative location of the spindle and mechanism has been once determined the 55 whole may be adjusted as a unit without varying such relative location.

Other purposes, objects and aspects of the invention will appear from the following description and will be more definitely pointed out in the appended claims. 60

For the purpose of fully describing the nature and advantages of the invention a specific embodiment thereof will be described as illustrated in the accompanying drawings. It should be understood, however, that 65 the invention is capable of various modifications and, therefore, it is not limited to the particular structure illustrated.

In the accompanying drawings Figure 1 is a plan view of the machine, the hopper 70 and associated mechanism having been removed. Fig. 2 is a front elevation of the machine. Fig. 3 is an end elevation from the right of Fig. 1. Fig. 4 is an end elevation from the left of Fig. 1. Fig. 5 is a detail elevation of the device for receiving the blank from the chute and its operating mechanism. Fig. 6 is a side elevation of the cam for operating the device for receiving the blanks from the chute. Fig. 7 is a developed view of said cam. Fig. 8 is a front elevation of the device for receiving the blank from the chute. Fig. 9 is a fragmentary plan of the end of the chute and the device for receiving the blanks therefrom. Fig. 10 is a fragmentary elevation of the picker fingers for carrying the blank and their operating mechanism. Fig. 11 is a front elevation of the picker fingers. Fig. 12 is a fragmentary longitudinal section 75 through the spindle. Fig. 13 is a transverse section through the spindle showing portions of the mechanism for operating it and the collet. Fig. 14 is a developed view of the cams for operating the spindle and collet. Fig. 15 is a fragmentary section showing 80 part of the mechanism for rotating the cam shaft. Fig. 16 is a side elevation of the cam for actuating the support or roller rest for the work and Fig. 17 is a developed view of 85 the cam for moving the tool. Fig. 18 is a side elevation of the support or roller rest for the work and Fig. 19 is a developed view of the cam for moving the tool. 90

The machine comprises a bed 1 on which is supported a drive shaft 2 provided with a drive pulley 3. The drive shaft carries a gear 4 which engages a gear 5 on a jack shaft 105 6. The jack shaft 6 also carries a gear 7 which engages a gear 8 on a second jack shaft 9. At its inner end the jack shaft 9 carries a bevel gear 10 which engages a bevel gear 11 on a transverse shaft 12 which carries a worm 13 engaging a worm gear 14 on a cam shaft 15. This train of gears may 110

provide for a reduction of speed between the drive shaft and the cam shaft and their relative speeds may be altered by replacing one or more of the gears.

- 5 The frame of the machine supports a hopper 16 into which headed blanks may be thrown promiscuously. The hopper 16 is provided with a chopper 17 of a well known form to properly arrange the blanks. A 10 roller 18 is carried by an arm 19 mounted on a transverse shaft 20 which carries a bevel gear 21 engaging a bevel gear 22 on a shaft 23 which also carries a sprocket 24 driven by a chain 25 passing over a sprocket 26 on 15 the cam shaft 15. As the arm 19 rotates it causes the roller 18 to wipe the arc shaped bottom 27 of the chopper 17, thereby causing it to rise and fall in the hopper to arrange the blanks in the well known way. A 20 spring 23^a on the shaft 23 allows the sprocket 24 to rotate on the shaft to relieve the mechanism should the chopper stick or be locked by misplaced blanks. The blanks are arranged in the chopper so as to hang by their 25 heads and at the upper end of the chopper stroke those so arranged slide by gravity into the chute 28 which, as shown, is provided with a guard 29 to keep the blanks in order.
- 30 At its lower or outlet end the chute 28 is provided at each side with a lock 30, which may be forked, pivoted at 31 on the chute side and forced by a spring 32 into the mouth of the chute so as to prevent blanks 35 from dropping out. (See Fig. 9.) The outer sides of the locks 30 are beveled toward their meeting point and each lock is provided with a set screw 33. It will be noted that the locks 30 as shown extend nearly to 40 the top edge of the chute 28 and so engage the lowermost bolt close under the head and thus the heavier head may be prevented from tipping the bolt or prematurely pulling it from the chute end.
- 45 A transverse shaft 34 carried in bearings 35 on the bed of the machine carries at one end a transverse carrier arm 36. At its other end the shaft 34 carries a pinion 37 which is engaged by a toothed arc 38 on one end of 50 an arm 39 pivoted on the bed at 40. At its other end the arm 39 carries a roller 41 adapted to be engaged by a cam 42 mounted on the cam shaft 15. The cam 42 is shown in elevation in Fig. 6 and developed in Fig. 55 7. A spring 43 mounted on the bed of the machine bears against the arm 39 and tends to hold the apparatus in position to cause the transfer arm 36 to be in a horizontal position. A stop 34^a adjustable on the shaft 34 60 engages a web 35 in the bed and limits the movement of the transfer carrier arm 36 as caused by the spring 43 to such as will cause the arm 36 to be substantially horizontal. As it rotates the cam 42 engages 65 the roller 41 so as to cause the toothed arc

38 to rotate the pinion 37 and swing the transfer carrier arm 36 through about 60° upward from the horizontal to the outlet of the chute 28.

The face of the transfer carrier arm 36 is beveled at 45 so that as it approaches the locks 30 the bevels 45 engage the set screws 33 or the bevel face in the locks 30 and so force them to separate against the pressure of the springs 32. The set screws 33 may be 70 adjusted to accommodate the transfer carrier arm and properly cooperate therewith and so as to cause the locks 30 to separate sufficiently to allow a blank to pass out between them. The set screws 33 may be adjusted so 75 that the bevels 45 engage not the screws but the beveled faces of the locks themselves or the screws 33 may be removed or omitted entirely. This allows the lowermost blank in the chute to drop by gravity into the cavity 80 46 on the transfer carrier arm 36. The transfer carrier arm, weighted down by the blank, then returns, under pressure of the spring 43, to its horizontal position, as allowed by the stop 35^a and the cam 42, carrying the blank with it. If it is found that the blank is heavy enough to depress the transfer carrier arm the spring 43 may be omitted. The locks 30 return, under pressure of the springs 32, to the position to hold 85 the remaining blanks in the chute as soon as the beveled faces 45 leave the set screws 33. A longitudinal shaft 47 mounted in the bed of the machine carries a rearwardly extending arm 48 on which is a roller 49 engaged by a cam 50 on the cam shaft 15. The shaft 47 also carries a forwardly extending arm 51 provided at its forward end with a fork 52 in which is a transverse pin 53. A coil spring 51^a fastened to the bed 1 90 and the arm 51 tends to hold the forward end of the arm substantially horizontal and also holds the roller 49 against the edge of the cam 50. In Fig. 1 a coil spring 51^b surrounding the shaft 47 may augment or replace the spring 51^a. Pivoted on the pin 53 95 are jaws 54 and 55 acting as picker fingers for the blank. At their tips the jaws or fingers 54 and 55 may be forked as shown in Fig. 11. The jaw 55 carries a set screw 110 56 by which the distance between the jaws may be regulated. A lug 57 depending from the fork 52 carries a set screw 58 which adjusts the position of the jaw 54 and consequently of the picker fingers as a unit with 115 relation to the arm 51. Extending upwardly and beyond the pivot pin 53 the jaws 54 and 55 have ends provided with holes through which passes a rod 59 projecting from a lug 60 extending upwardly from the 120 fork 52. Surrounding the rod 59 and between the ends of the jaws 54 and 55 is a coil spring 61 tending to force together the lower ends of the jaws as allowed by the 125 set screw 56. A coil spring 62 surrounds 130

- the rod 59 between the lug 60 and the jaw 54 and tends to hold the jaws as a unit against the set screw 58. The picker fingers thus are normally held in fixed positions but they are held resiliently and are capable of suiting themselves either separately and individually or as a unit to the pieces and parts with which they co-act or engage.
- 10 The transfer carrier arm 36 swings in a plane which is a continuation of the plane of the chute 28 and the arm 51 is so mounted and operated that it may extend the gripper fingers into the same plane. The transfer carrier arm receives the blanks in a substantially upright position and moves them to a substantially horizontal position. The cam 50 is so formed and timed as to cause the picker fingers made up of the jaws 54 and 55 to descend upon and grasp the blank in the horizontal transfer carrier arm 36. The springs 61 and 62 give sufficiently to allow the fingers 54 and 55 or their forked tips to separate and enter the openings 63 through the bevels 45 and the sides of the cavity 46 in the carrier arm 36. The picker fingers now may grasp the blank and remove it from the carrier 36 as the cam 50 causes the arm 51 to rise. The picker fingers rise to allow the transfer carrier arm 36 to move past them toward its upright position and then the picker fingers move back and further downward past their former position so as to bring the blank 20 about on the level with a collet 64. The blank is maintained substantially horizontal so long as it is held by the picker fingers in which position it is grasped and rotated by the collet.
- 20 Pivoted on the shaft 47 is an arm 65 which is connected to the arm 51 by a spring 66. The forward end of the arm 65 may have two fingers 67 and 68. The finger 67 extends between the prongs of the forked end of the picker fingers. The finger 68 extends adjacent the picker fingers on the side away from the transfer carrier arm 36. The spring 66 tends normally to hold the fingers 67 and 68 of the arm 65 above the gripping surface of the picker fingers 54 and 55 so that they are free to grasp a blank. The arm 65 being loosely mounted on the shaft 47 is free to move with the arm 51. When the arm 65 has been carried by the arm 51 to nearly the upward limit of movement of the arm 51, a projection 69 from the arm 65 engages a pin 70 extending from the bed of the machine. At this point the pin 70 stops the further movement of the arm 65 and expands the spring 66 as the arm 51 moves further upward. At this time the gripping jaws 54 and 55 wipe past the fingers 67 and 68 which causes any blank carried thereby to be ejected. The normal movement of the picker fingers after receiv-
- ing the blank from the transfer carrier 36 is upward a slight distance but less than their full upward movement. This movement does not bring the kick out fingers 67 and 68 into operation. Normally the 70 picker fingers then move downward and deliver the blank to the collet. If, however, the blank is misshapen or misplaced or for any reason it is not grasped by the collet it may be retained in the picker fingers in their 75 final movement to their full upward position. In this event the pin 70 causes the blank so carried to be ejected from the picker fingers which are thus left empty and prepared to receive the next blank presented to 80 them by the transfer carrier arm 36.
- Extending laterally from the fork 52 which carries the picker fingers 54 and 55 is an arm 71 provided with a socket 72 in which is a coil spring 73 on which 85 rests a plunger 74. The arm 71 extends from the side of the fork 52 which is away from the transfer carrier arm 36 and the plunger 74 is held at such a position that it is approximately in alignment with the gripping point of the picker fingers 54 and 55. The head of the blank lifted from the transfer carrier arm 36 by the picker fingers 54 and 55 rests against the plunger 74 which being supported by the spring 73 allows 90 blanks of varying sizes and variously positioned in the transfer carrier arm 36 to be properly received by the picker fingers 54 and 55. If not grasped by the collet the blanks may be forced, by contact of the 95 moving spindle, against the spring supported plunger 74. The springs 61 and 62 allow the fingers 54 and 55 to give sufficiently to permit the blank to slide through the fingers and compress the spring 73. This prevents 100 the apparatus from jamming or becoming injured or disarranged.
- 105 The drive shaft 2 carries a long gear 90 which slidably engages a gear 91 on a reciprocating spindle 92 carried in an adjustable head 93 resting on the bed of the machine. The long gear 90 may be held in place on the drive shaft 2 by means of a set screw so that it is adjustable along the shaft. The adjustable head 93 carries a transverse 110 rod 171 on which are the bearings 172 for a yoke 173 from which extends rearwardly an arm 174 carrying a roller 75 which is engaged by a cam 76 mounted on a drum 77 which is adjustably held on the cam shaft 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

to cause the collet to advance and surround the blank brought into alignment with it by the picker fingers 54 and 55. A stop 88 is held in the base of the head 93 by screws or bolts 89 in such position as to be engaged by the trunnion ring 82 so as to limit the forward movement of the collet carried by the spindle. On the rear end of the shaft 171 is fastened by a set screw 94 a rearwardly extending arm 95 carrying a roller 96 which may be engaged by a cam 97 carried on the drum 77 on the cam shaft 15. Mounted on the forward end of the shaft 171 by a set screw 97 is a downwardly extending arm 98 which engages a link 99 extending to the left in Fig. 2 to engage one arm of the yoke 100 pivoted at 101 to a lug 102 extending from the head 93. The yoke 100 engages a collar 103 of a cone 104 mounted to slide on the spindle 92. Angle levers 105 pivoted on a disc 106 have forwardly extending arms 187 engaged by the cone 104. The levers 105 have weighted extensions 108. The disc or collar 106 is pinned to a shaft 107 which extends through the center of the spindle 92. The jaws 208 of the collet 64 are screwed to the end of the shaft 107 opposite the end carrying the disc 106. Surrounding the shaft 107 is a coil spring 109 resting between the inner end of the jaws 208 and the bottom 110 of a socket in the spindle 92. Within the shaft 107 and at the end carrying the collet is a long socket in which rests a plunger 111 on a coil spring 112. The outer end of the plunger 111 normally rests between the jaws 208 of the collet. The outer side of the jaws 208 of the collet are beveled and engage correspondingly beveled surfaces of a hood 117 mounted on the end of the spindle 92.

The spindle 92 is continuously rotated through the gears 90 and 91 and centrifugal force working on the weighted ends 108 of the levers 105 keeps the arms 187 in contact with the surface of the cone 104. Movement of the cone 104 toward the right in Fig. 2 will therefore tend to draw the disc 106 toward the end of the spindle 92. This will force the shaft 107 to the right in Fig. 12 and co-operate with the expanding spring 109 to allow the collet jaws 208 to ride to the right through the hood 117 and so open to release a blank and to be in condition to receive a blank. A blank held in the picker fingers 54 and 55 with its head resting against the spring supported plunger 74 will be approached by the collet as the spindle advances in such a way as to cause the plunger 111 to engage the free end of the shank of the blank. The spring 73 is strong enough to overcome the spring 112. The plunger 111 will thus be depressed and the spring 112 compressed as a blank is grasped by the collet jaws 208. When therefore the collet jaws 208 are freed from the blank, the

spring 112 will cause the plunger 111 to eject the blank from the collet.

The cams 76 and 97 are so arranged and associated with the other parts of the machine that the spindle is reciprocated to approach the blank and cause the collet to surround it. The cone 104 is then shifted to cause the collet to close and the parts are held in this position while the cutting operation is performed. Then the cone 104 is shifted to open the collet as the spindle recedes to allow the finished blank to be ejected and another supplied.

After the blank has been grasped by the collet and the picker fingers 54 and 55 have been withdrawn therefrom a back rest (here shown as rollers 119 and 120) may be brought into engagement with the blank preferably just below its head. An angle lever 121 pivoted on the frame of the machine carries at its upper end a bolt 122. Partly surrounding the bolt 122 is a half bearing in an arm 123 which carries the roller 119. Partly surrounding the bolt 122 is a half bearing of an arm 124 carrying the roller 120. The split bearings of the arms 123 and 124 engage and limit the separating movements of the rollers 119 and 120 caused by their coming in contact with the rotating blank. Set screws 125 carried by the lever 121 may also be provided to limit the movement of the arms 123 and 124. The lower end of the lever 121 is engaged by a link 126 connected to the lower arm 127 of an angle lever pivoted at 128 to the bed of the machine. The other arm 129 of the angle lever carries a roll 130 which may be engaged by a cam 131 on the cam shaft 15. The form of the cam 131 is shown in detail in Fig. 16. A turn buckle 132 is provided on the link 126 to vary and adjust its length. Between the turn buckle 132 and the bearing 133 in the bed for the link 126 is a coil spring 134 surrounding the link and tending to hold the roller rests 119 and 120 out of the path of the blank. The cam 131, however, engages the roller 130 and compresses the spring 134 and causes the rollers 119 and 120 to engage the blank and support it as it rotates.

A transverse slide 136 in the bed of the machine is provided at its rear end with a roll 137 which may be engaged by a cam 138 on the cam shaft 15. Depending from the slide 136 is a lug 139 resting against a coil spring 140 on an abutment 141 in the bed of the machine. The tendency of the spring 140 is to force the slide 136 toward the right in Fig. 3 and so keep the roll 137 in contact with its cam 138.

Resting in transverse ways 142 in the slide 136 is a tool block 143 which may carry tools 144 and 145 of any suitable shape. To a projection 146 on the tool block 143 is pivoted one end of a lever 147. The other end of the lever 147 extending to the rear

of the machine, carries a roller 148 riding in a scroll cam 149 on the cam shaft 15. The cam 149 is shown developed in Fig. 17. Passing through a longitudinal slot 150 in the center of the lever 147 is the vertical pivot pin 151 tapped into a plate 220 slidably mounted on the bed of the machine. Rising from the lever arm 147 at each end of the slot 150 is a lug 152 in which is an adjusting bolt or screw 153 provided with a lock nut 154. The bolts 153 engage a bearing collar 153^a on the pivot pin 151. By turning and adjusting the bolts 153 the position of the plate 220 and thus of the pivot pin 151 in the slot 150 may be varied and thus may be varied the throw of the forward end of the lever 147 engaging the tool block 143. When desired either tool may be omitted and the machine operate with one suitably formed tool.

At the time the blank is delivered to the collet, the roller rests 119 and 120 are withdrawn from the path of the blank and the slide 136 carrying the tools 144 and 145 is retracted toward the right in Fig. 3. After the blank has been grasped by the collet and while being held and rotated the roller rests 119 and 120 advance and support the blank and then the slide 136 is forced toward the blank. At this time the cutting tools are about in the position shown in Fig. 1 where the tool 144 is below the head of the blank and the tool 145 is beyond the head of the blank. After the tools have been advanced toward the blank in a direction transverse to its axis the cam 149 causes the lever 147 to shift the tool block 143 in a direction parallel to the axis of the rotating blank, first in one direction and then in the other so that the tool 144 will shave under the head of the blank or bolt and then the tool 145 will shave or finish the top of the head or the operation might be reversed. It will be noted that the movement of the tool 144 will tend to draw the spindle toward the right in Fig. 2 and this thrust movement may be taken up by the trunnion collar 82 engaging the stop 88 in the spindle head 93.

The rollers 119 and 120 act as steadyng supports for the rapidly rotating blank when it is being acted on by the cutting tools 144 and 145. After the cutting operation has been completed the cutting tools and the rollers are withdrawn and the blank may be dropped from the collet and another put in place without interference.

The positioning plunger 74 tends to assure the blank being so placed that when grasped in the collet the head will be in position to be between the cutters 144 and 145 when they are advanced to the blank.

The spindle head 93 may be adjusted along the bed of the machine toward and from the picker fingers and the tool slide 136 to provide for operation upon blanks of

different lengths. A hand wheel 113 operating a gear 114 engaging a rack 115 in a well known way provides for movement of the spindle head. The usual bolts 116 are provided for holding the head in any of its 70 adjustments. The gear 90 may be held on the driving shaft by a set screw so that it may be adjusted along the driving shaft as the spindle head 93 is adjusted and thus the spindle may be rotated in whatever position 75 the spindle head may be. Likewise the drum 77 carrying the cams for operating the spindle and collet may be adjusted along the cam shaft 15 and held by a set screw 78 so that the spindle may be properly reciprocated and the collet operated in any adjusted 80 position the head 93 may take.

Extending to the rear from the head 93 are arms 118 between which rotates the drum 77 carrying the cams 76 and 97 for 85 operating the spindle and the collet. When the cams have been set to properly cooperate to operate the spindle and collet the entire apparatus may be adjusted along the bed 90 of the machine so as to accommodate blanks of various lengths by loosening the bolts 116 holding the head 93 and the set screw 78 holding the cam drum 77. The head 93 may now be moved and the arms 118 will cause the cams 76 and 97 to move with it 95 without losing their relative locations. The set screw holding the gear 90 may be loosened also and the gear 90 shifted along the drive shaft 2 if necessary.

It will be seen that in normal operation 100 the transfer carrier arm 36 will receive a blank from the chute and deliver it into the picker fingers 54 and 55 which will lower it into position to be grasped by the collet jaws 208 as the spindle 92 advances. The rollers 119 and 120 will then advance to support the blank. The tools 144 and 145 will then advance above and below the head of the blank. Lateral movement will be given to the tools to cause them to attack the work. They and the rollers will then recede and the finished blank will be ejected by the plunger 111 as the collet opens and recedes with the moving spindle to clear the space for receipt 105 of the next blank.

The machine has been described as operating on headed blanks but in some aspects the invention is applicable to action on work of other types.

I claim as my invention:

1. In the machine of the class described, a head, a spindle in the head, means for reciprocating the spindle in the head, a stop in the head to limit the spindle movement, 125 a collet in the spindle, picker fingers for placing a headed blank in alignment with the spindle as it reciprocates, a spring supported plunger carried by the fingers to determine the position of the blank in the collet, a kick out device adjacent the fingers, 130

- means for operating the collet at one end of the spindle movement so as to grasp the blank by its shank, a spring within the collet, a plunger compressing the spring within the collet, a roller rest, means for advancing the roller rest to engage the blank below its head while it is held in the collet, means for rotating the spindle carrying the blank, a tool slide, tools on the tool slide, means for moving the tools transversely to the axis of the blank in the collet, and means for moving the tools to cut under the head of the blank.
5. In the machine of the class described, a head, a spindle in the head, means for reciprocating the spindle in the head, a collet in the spindle, picker fingers for placing a headed blank in alignment with the spindle as it reciprocates, a spring supported plunger carried by the fingers to determine the position of the blank in the collet, a kick out device adjacent the fingers, means for operating the collet at one end of the spindle movement so as to grasp the blank by its shank, a spring within the collet, a plunger compressing the spring within the collet when the spindle reciprocates, a roller rest, means for advancing the roller rest to engage the blank below its head while it is held in the collet, means for rotating the spindle carrying the blank, a tool slide, tools on the slide, means for moving the tools transversely to the axis of the blank in the collet, and means for moving the tools parallel to the axis of the blank.
3. In the machine of the class described, a head, a spindle in the head, means for reciprocating the spindle in the head, a collet in the spindle, picker fingers for placing a headed blank in alignment with the spindle as it reciprocates, means for operating the collet at one end of the spindle movement so as to grasp the blank by its shank, a spring within the collet, a plunger compressing the spring within the collet when the spindle reciprocates, a roller rest, means for advancing the roller rest to engage the blank below its head while it is held in the collet, means for rotating the spindle carrying the blank, a tool slide, tools on the tool slide, means for moving the tools transversely to the axis of the blank in the collet, and means for moving the tools parallel to the axis of the blank.
4. In the machine of the class described, a head, a spindle in the head, means for reciprocating the spindle in the head, a collet in the spindle, picker fingers for placing a headed blank in alignment with the spindle as it reciprocates, a spring supported plunger carried by the fingers to determine the position of the blank in the collet, a kick out device adjacent the fingers, means for operating the collet at one end of the spindle movement so as to grasp the blank by its shank, a spring within the collet, a plunger compressing the spring within the collet when the spindle reciprocates, a roller rest, means for advancing the roller rest to engage the blank below its head while it is held in the collet, means for rotating the spindle carrying the blank, a tool, and means for causing the tool to attack the blank.
5. A head, a spindle in the head, a collet in the spindle, a shaft in the head, means carried by the shaft to reciprocate the spindle, and means carried by the shaft to operate the collet.
6. A head, a spindle in the head, a collet in the spindle, a shaft in the head, means carried by the shaft to reciprocate the spindle, means carried by the shaft to operate the collet, and cams to operate the said means.
7. A spindle, means for rotating the spindle, a collet in the spindle, means for feeding a blank to the collet, a back rest, means for causing the back rest to engage and support the rotating blank in the collet, and means for operating on the work while so rotated and supported.
8. A head, a spindle in the head, a collet on the spindle, means for reciprocating the spindle and for operating the collet, and arms on the head between which the means rest.
9. A bed, a head adjustable along the bed, a spindle in the head, a cam shaft on the bed, a cam on the cam shaft for reciprocating the spindle, and means to cause the cam to be adjusted along the cam shaft when the head is adjusted along the bed.
10. A bed, a head adjustable along the bed, a spindle in the head, a cam shaft on the bed, a cam on the cam shaft for reciprocating the spindle, means to cause the cam to be adjusted along the cam shaft when the head is adjusted along the bed, a driving shaft, an adjustable gear on the driving shaft to rotate the spindle, and means to hold in their adjusted position the head, cam and gear.
11. A bed, a head adjustable along the bed, a spindle in the head, a cam shaft on the bed, a cam on the cam shaft for reciprocating the spindle, a collet in the spindle, a cam on the cam shaft for operating the collet, and means to cause the cams to be adjusted along the cam shaft when the head is adjusted along the bed.
12. A bed, a head adjustable along the bed, a spindle in the head, a cam shaft on the bed, a cam on the cam shaft for reciprocating the spindle, a collet in the spindle, a cam on the cam shaft for operating the collet, means to cause the cams to be adjusted along the cam shaft when the head is adjusted along the bed, a driving shaft, an adjustable gear on the driving shaft to rotate the collet.

the spindle, and means to hold in their adjusted position the head, cams and gear.

13. A bed, a head adjustable along the bed, a spindle in the head, means for reciprocating the spindle, and means to cause the reciprocating means to be adjusted when the head is adjusted.

14. A bed, a head adjustable along the bed, a spindle in the head, means for reciprocating the spindle, means to cause the reciprocating means to be adjusted when the head is adjusted, and means for holding the parts in their adjusted positions.

15. A bed, a head adjustable along the bed, a spindle in the head, a collet in the spindle, means for reciprocating the spindle and for operating the collet, means to cause the said means to be adjusted when the head is adjusted, and means to hold the parts in adjusted positions.

16. A bed, a head adjustable along the bed, a spindle in the head, means for reciprocating the spindle, a collet in the head, means for operating the collet, and means to cause the said means to be adjusted when the head is adjusted.

17. A bed, a head adjustable along the bed, a spindle in the head, means for reciprocating the spindle, and means to cause the said means to be adjusted when the head is adjusted, adjustable means for rotating the spindle, and means for holding the various parts in their adjusted positions.

18. A rotating work holder, a tool slide, a spring holding the tool slide away from the work, a cam for forcing the slide against the spring and toward the work, transverse ways in the slide, a tool block in the ways, tools held in the block, a lever engaging the block, an adjustable pivot for the lever, and a cam engaging the lever to cause the block to move in the transverse ways to attack the work.

19. A rotating work holder, a tool slide, a spring holding the tool slide away from the work, a cam for forcing the slide against the spring and toward the work, transverse ways in the slide, a tool block in the ways, tools held in the block, a lever engaging the block, and a cam engaging the lever to cause the block to move in the transverse ways to attack the work.

20. A rotating work holder, a tool slide, a cam for forcing the slide toward the work, transverse ways in the slide, a tool block in the ways, tools held in the block, a lever engaging the block, an adjustable pivot for the lever, and a cam engaging the lever to cause the block to move in the transverse ways along the work to attack the same.

21. A rotating work holder, a tool slide, a cam for forcing the slide toward the work, transverse ways in the slide, a tool block in the ways, tools held in the block, a lever engaging the block, and a cam engaging the

lever to cause the block to move in the transverse ways along the work to attack the same.

22. A rotating work holder, a tool slide, a spring holding the tool slide away from the work, a cam for forcing the slide against the spring and toward the work, transverse ways in the slide, a tool block in the ways, tools held in the block, and a cam to cause the block to move in the transverse ways to attack the work.

23. A rotating work holder, a tool slide, a cam for forcing the slide toward the work, transverse ways in the slide, a tool block in the ways, tools held in the block, and a cam to cause the block to move in the transverse ways to attack the work.

24. A rotating work holder, a tool slide, means for forcing the slide toward the work, transverse ways in the slide, tools in the ways, and cam means to cause the tools to move in the transverse ways along the work to attack the same work.

25. A rotating work holder, a tool slide, means for forcing the slide toward the work, a tool block on the slide, and means to automatically cause the tool block to move transversely of the slide.

26. A rotating work holder, a tool slide, means for forcing the slide toward the work, transverse ways in the slide, a tool block in the ways, tools held in the block, a lever engaging the block, and a cam engaging the lever to cause the block to move in the transverse ways to move said tools along the work to attack the same.

27. A rotating work holder, a tool slide, means for forcing the slide toward the work, a tool block on the slide, a lever engaging the block, and a cam engaging the lever to cause the block to move transversely of the slide to move said tools along the work to attack the same.

28. A rotating work holder, a tool slide, means forcing the slide toward the work, tools on the slide, a lever engaging the tools, an adjustable pivot for the lever, and a cam engaging the lever to cause the tools to move transversely of the slide to attack the work.

29. A rotating work holder, a tool slide, means for forcing the slide toward the work, tools on the slide, a lever engaging the tools, and cam means automatically to cause the tools to move transversely of the slide.

30. Pick up fingers for grasping a blank, a pivoted arm carrying the fingers, means for swinging the arm on its pivot, a kick out arm on the pivot, means for holding the pivoted arm and kick out together resiliently, and means to cause the kick out arm to remain stationary before the pivoted arm reaches the limit of its travel in one direction.

31. Pick up fingers for grasping a blank,

- 3 a pivoted arm carrying the fingers, means for swinging the arm on its pivot, a kick out arm on the pivot, means for holding the pivoted arm and kick out to move together, and means to cause relative movement between the pick up fingers and kick out.
- 5 32. Pick up fingers for grasping a blank, an arm carrying the fingers, means for swinging the arm, a kick out arm, means for holding the pivoted arm and kick out together resiliently, and means to cause the kick out arm to remain stationary before the pivoted arm reaches the limit of its travel in one direction.
- 10 33. Pick up fingers for grasping a blank, an arm carrying the fingers, means for swinging the arm, a kick out arm, means for holding the pivoted arm and kick out together resiliently, and means to cause relative movement between the pick up fingers and kick out.
- 15 34. Pick up fingers for grasping a blank, a kick out arm, means for swinging the arm and fingers together, and means to cause the kick out arm to remain stationary before the pivoted arm reaches the limit of its travel in one direction.
- 20 35. Pick up fingers for grasping a blank, a kick out arm, means for swinging the arm and fingers together, and means to cause relative movement between the pick up fingers and kick out.
- 25 36. Pick up fingers for grasping a blank, means for swinging the fingers, a kick out, means for holding the fingers and kick out together resiliently, and means to cause the kick out arm to remain stationary before the pivoted arm reaches the limit of its travel in one direction.
- 30 37. Pick up fingers for grasping a blank, means for swinging the fingers, a kick out, means for holding the fingers and kick out together, and means to cause relative movement between the fingers and kick out.
- 35 38. A bed, a stop thereon, a spindle, a collar thereon, a collet in the spindle, and means for forcing the spindle so that the collar engages the stop.
- 40 39. A bed, a stop thereon, a spindle, a collar thereon, a collet in the spindle, means for forcing the spindle so that the collar engages the stop, a cutting tool, and means to cause the cutting tool to attack work in the collet so as to take the tool thrust on the stop.
- 45 40. A bed, a stop thereon, a spindle, a collar thereon, a collet in the spindle, means for forcing the spindle so that the collar engages the stop, a cutting tool, means to cause the cutting tool to attack work in the collet so as to take the tool thrust on the stop, and a roller rest for the work in the collet.
- 50 41. A bed, a stop thereon, a spindle, a collar thereon, a collet in the spindle, means for forcing the spindle so that the collar en-
- gages the stop, a cutting tool, means to cause the cutting tool to attack work in the collet so as to take the tool thrust on the stop, a roller rest for the work in the collet, and means for removing the rest from the work after the cutting operation.
- 55 42. Picker fingers for carrying a blank, and a resiliently mounted positioning bar carried by the fingers and engaging the blank.
- 60 43. Picker fingers for carrying a blank, a resiliently mounted positioning bar carried by the fingers and engaging the blank, and a resiliently mounted arm carried by the fingers for ejecting a blank therefrom.
- 65 44. Resiliently supported picker fingers for carrying a blank, a resiliently mounted plug engaging the head of the blank, a collet, means for moving the fingers to place the blank in alignment with the collet, a resiliently mounted plunger within the collet, means to cause the plunger to engage the free end of the blank, and means to cause the collet to grasp the blank while held in the fingers between the plug and plunger.
- 70 45. Resiliently supported picker fingers for carrying a blank, a resiliently mounted plug engaging the head of the blank, a collet, means for moving the fingers to place the blank in alignment with the collet, a resiliently mounted plunger within the collet, means to cause the plunger to engage the free end of the blank, means to cause the collet to grasp the blank while held in the fingers between the plug and plunger, and means for withdrawing the fingers and plug from the blank.
- 75 46. Resiliently supported picker fingers for carrying a blank, a resiliently mounted plug engaging the head of the blank, a collet, means for moving the fingers to place the blank in alignment with the collet, and means to cause the collet to grasp the blank while held in the fingers.
- 80 47. Resiliently supported picker fingers for carrying a blank, a resiliently mounted plug engaging the head of the blank, a collet, means for moving the fingers to place the blank in alignment with the collet, means to cause the collet to grasp the blank while held in the fingers, a roller rest for the blank, means for causing the rest to approach the blank in the collet, cutters, means to cause the cutters to travel transversely to the axis of the blank, and means to cause the cutters to travel parallel with the axis of the blank.
- 85 48. Resiliently supported picker fingers for carrying a blank, a resiliently mounted plug engaging the head of the blank, a collet, means for moving the fingers to place the blank in alignment with the collet, means to cause the collet to grasp the blank while held in the fingers, cutters, means to cause the cutters to travel transversely to the axis of the blank, and means to cause the cutters to travel parallel with the axis of the blank.
- 90 49. Resiliently supported picker fingers for carrying a blank, a resiliently mounted plug engaging the head of the blank, a collet, means for moving the fingers to place the blank in alignment with the collet, means to cause the collet to grasp the blank while held in the fingers, cutters, means to cause the cutters to travel transversely to the axis of the blank, and means to cause the cutters to travel parallel with the axis of the blank.
- 95 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

the cutters to travel transversely to the axis of the blank, and means to cause the cutters to travel parallel with the axis of the blank.

49. Resiliently supported picker fingers for carrying a blank, a resiliently mounted plug engaging the head of the blank, a collet, means for moving the fingers to place the blank in alignment with the collet, means to cause the collet to grasp the blank while held in the fingers, cutters, and means to cause the cutters to travel parallel with the axis of the blank.

50. A pair of picker fingers; means for moving the fingers down to grasp a blank, then up, then down beyond their first down position, and then up beyond their first up position; and means for ejecting a blank from the fingers at their final up position.

51. A pair of picker fingers; means for moving the fingers down to grasp a blank, then up, then down beyond their first down position, and then up beyond their first up position; and means carried by the fingers for ejecting a blank from the fingers at their final up position.

52. A pair of picker fingers; means for moving the fingers down to grasp a blank, then up, then down beyond their first down position, and then up beyond their first up position; a collet for grasping the blank when the fingers are in their lowermost position; and means for ejecting a blank from the fingers at their final up position.

53. A pair of picker fingers; means for moving the fingers down to grasp a blank, then up, then down beyond their first down position and then up beyond their first up position; means carried by the fingers to position a blank therein; and means for ejecting a blank from the fingers at their final up position.

54. A pair of picker fingers; means for moving the fingers down, then up, then down beyond their first down position, and then up beyond their first up position; means for supplying a blank to the fingers at their first down position; and means for ejecting a blank from the fingers at their final up position.

55. A spindle, a collet in the spindle, a spring supported rod within the collet,

means for causing the collet to grasp a blank while it rests against the rod on the compressed spring, and means for opening the collet to allow the spring to expand and kick out the blank.

56. A spindle, means for rotating the spindle, a collet in the spindle, means for feeding a blank to the spindle, a roller rest, means for causing the roller rest to engage and support the rotating work in the spindle, and means for operating on the work while so rotated and supported.

57. A spindle, means for rotating the spindle, a collet in the spindle, means for feeding a blank to the spindle, a roller rest, means for causing the roller rest to engage and support the rotating work in the spindle, means for operating on the work while so rotated and supported, and means for withdrawing the roller rest from the work.

58. A roller rest, a pivoted angle lever supporting the rest, a link engaging the lever, a bearing for the link, an adjusting turn buckle on the link, a spring between the buckle and bearing tending to hold the rest from the work, and means to cause the link to compress the spring and advance the rest to the work.

59. A head, a spindle in the head, a collet in the spindle, a shaft in the head, and means carried by the shaft to operate the collet.

60. A head, a spindle in the head, a collet in the spindle, a shaft in the head, means carried by the shaft to operate the collet, and a cam to operate the said means.

61. A head, a spindle in the head, a cam for reciprocating the spindle, a collet in the spindle, a cam for operating the collet, and arms on the head between which the cams rest.

62. A head, a spindle in the head, a cam for reciprocating the spindle, and arms on the head between which the cam rests.

63. A head, a spindle in the head, a cam for reciprocating the spindle, a collet on the spindle, a cam for operating the collet, and means on the head for determining the position of the cam.

MICHAEL J. RILEY.
